OTTO E. DENIVELLE, OF MOUNT VERNON, NEW YORK.

SLEEPING-EYES FOR DOLLS.

1,177,393.

Specification of Letters Patent. Patented Mar. 28, 1916.

Application filed September 16, 1915. Serial No. 50,998.

To all whom it may concern:

Be it known that I, OTTO E. DENIVELLE, a citizen of the United States, and a resident of Mount Vernon, in the county of 5 Westchester and State of New York, have invented new and Improved Sleeping-Eyes for Dolls, of which the following is a full, clear, and exact description.

One object of the invention is to provide 10 new and improved sleeping eyes for dolls, arranged to permit each eye to move into open or closed position independently one of the other to insure free movement of the eyeballs.

15 Another object is to provide a simple and durable construction to allow of manufacturing the doll's head very economically.

In order to produce the desired result, use 20 is made of metallic sockets cast into the plastic material of the doll's head, each socket having an opening corresponding to the edges of the eyelids and an eyeball mounted in each socket and having a representation of the iris of the human eye, attached to the eyeball by way of the said 25 opening after the parts are assembled, to insure correct location of the iris on the eyeball relatively to the said opening.

A practical embodiment of the invention 30 is represented in the accompanying drawings forming a part of this specification, in which similar characters of reference indicate corresponding parts in all the views.

Figure 1 is a cross section of a doll's head 35 in upright position and provided with the improved sleeping eyes; Fig. 2 is a like view of the same with the doll's head in horizontal position and the sleeping eyes closed; Fig. 3 is a similar view with the doll's head 40 in upwardly inclined position; Fig. 4 is a sectional rear elevation of the doll's head on the line 4-4 of Fig. 1; Fig. 5 is a cross section of a portion of the doll's head at one of the eyes and with the eyeball removed; 45 and Fig. 6 is an enlarged cross section of one of the eyeballs.

The doll's head 10 is made of a suitable 50 plastic material and is provided at the eye openings 11 with spherical sockets 12, preferably of metal cast into the material of the head 10, at the time the latter is in a plastic condition in the mold so that the sockets 12 on the hardening of the plastic material are securely fastened in position in

the head 10 and are not liable to shrink 55 thus forming a proper bearing for the eyeballs 13. Each socket 12 is provided at the front with an opening 14 of almond shape with the edge corresponding to the edges of the eye opening 11, that is, to the edges of the 60 eyeballs. Centrally through the edges of the eyeballs 13 extends a pivot 15 also passing through the side walls of the corresponding sockets 12 so that the eyeballs 13 are securely held in place and the eyeballs are axially 65 mounted to turn in the sockets 12. The ends of each pin 15 beyond the sockets 12 are embedded in the plastic material of the head 10 to aid in holding the sockets 12 in position in the head 10. Each socket 12 is 70 slightly in excess of a hemisphere so that the rear portion of each socket is open. Each of the eyeballs 13 is provided with a counterweight 16, preferably in the form of a nail, the angular point of which is soldered 75 or otherwise fastened to the rear of the eyeball 13 so that the counterweight 16 extends downward, as plainly indicated in the drawings. It will be noticed that by the arrangement described, the weight 16 is free 80 of the socket 12 to turn the eyeball 13 freely in the socket 12 whenever the head 10 is moved from a vertical position into horizontal or rearwardly inclined position or vice versa. When the head 10 is held in 85 upright or forwardly inclined position, as shown in Figs. 1 and 3, then the counterweight 16 abuts against the rear edge of the socket 12 thus limiting the opening movement of the eyeball 13. 90

Each of the eyeballs 13 has its body preferably made of metal in the form of a cup, and on the front face of the said body is pasted, cemented or otherwise fastened a disk 17 of paper or the like material and 95 having printed thereon a representation of the iris of the human eye. The portions of the body of the eyeball 19 adjacent the sides and the bottom of the disk 17 are provided with a coating 18 of white enamel, 100 and the portion of the eyeball body 19 above the disk 17 is provided with a coating 19 of flesh color so that when the eyeballs 13 are in sleeping position, as shown in Fig. 2, then this flesh colored coating appears in the 105 opening 14 thereby giving a natural appearance to the sleeping eye. The disk 17 as well as the coatings 18 and 19 are prefer-

ably covered with a coating 20 of transparent varnish to give the desired luster to the eye. In the manufacture of the doll's head the eyeball 13 is provided with the 5 coverings 18 and 19 after which the parts are assembled by mounting the eyeballs 13 on the pivot 15. The operator now holds the doll's head 10 in upright or forwardly inclined position, as shown in Figs. 1 and 3, 10 so that the counterweights 16 abut against the sockets 12, after which the operator fastens the disk 17 to each eyeball 13 by way of the opening 14 so that the disk 17 is accurately located relatively to the opening 14, 15 so that the eyes appear natural when the doll's head 10 is held in upright or forwardly inclined position, and likewise when the doll's head is placed in horizontal position the disks 17 disappear from the openings 14 and the flesh colored coating 13 appears within the said openings thus giving the doll a sleeping appearance.

From the foregoing it will be seen that by embedding the metallic sockets 12 in the 25 plastic material of the head 10 and mounting the eyeballs 13 in the said sockets the eyeballs are at all times free to turn thus insuring a quick opening and closing movement of the eyes when moving the head 10, 30 from vertical into horizontal position or vice versa. It will also be noticed that by the use of the metallic socket 12 the shrinking of the plastic material during the setting thereof does not cause a shrinking of the sockets 25 and consequently the eyeballs 13 are not liable to bind in the sockets.

Having thus described my invention, I

claim as new and desire to secure by Letters Patent:

1. A doll's head provided with eye sockets 40 cast in the material of the head, pivot-rods passing through the sockets and each having one end embedded in a side wall of the head, a metallic cup-shaped eye ball loosely mounted on each pivot-rod, each eye ball 45 having a printed representation of the iris of the eye and provided at the sides and bottom of the iris with a coating of white enamel and above the iris with a coating of flesh color; and counterweights having angular ends secured to the inner faces of the eye balls so as to project downwardly and to engage the eye sockets to limit the opening movement of the eye balls.

2. A doll's head provided with eye sockets 55 cast in the material of the head, pivot rods passing through the sockets, and each having one end embedded in a side wall of the head, a cup-shaped eye ball loosely mounted on each rod in the socket, and counterweights having angular ends secured to the rear inner faces of the eye balls, said counterweights extending downwardly and adapted to engage the said sockets to limit the opening movement of the eye balls when the head is held either in an upright or forwardly inclined position.

In testimony whereof I have signed my name to this specification in the presence of two subscribing witnesses.

OTTO E. DENIVELLE.
